UNITED STATES PATENT OFFICE.

JOSEPH RICHARD PURVIS AND GEORGE HENRY MOSES, OF TODMORDEN, ONTARIO, CANADA.

COMBINED TAIL LIGHT AND LICENSE-MARKER HOLDER.

Application filed October 3, 1921. Serial No. 505,141.

To all whom it may concern:

Be it known that we, JOSEPH RICHARD PURVIS and GEORGE HENRY MOSES, both subjects of the King of Great Britain, and both 5 residents of the village of Todmorden, in the county of York, in the Province of Ontario, Canada, have invented certain new and useful Improvements in Combined Tail Lights and License-Marker Holders, of 10 which the following is the specification.

Our invention relates to improvements in combined tail light and license marker holders and the object of the invention is to construct a simple and effective device in 15 which the numbers on the marker while being clearly visible by day will be capable of being illuminated by night, said license number plates being constructed of translucent material.

20 A further object is to provide means for supporting the marker plate in position in the holder and a still further object is to devise a holder that will be dust and watertight.

25 Our invention consists of a combined tail light and license marker holder constructed and arranged substantially as hereinafter more particularly described and illustrated in the accompanying drawing in which:

30 Fig. 1 represents a perspective view of the device constructed according to our invention.

Fig. 2 is an elevational view of the inside of the back portion thereof with the front 35 removed.

Fig. 3 is a cross sectional view, and

Fig. 4 is a perspective detail of the means for securing the marker plate in position in the holder.

40 Like characters of reference indicate corresponding parts in the different views.

1 is the front of the holder provided with a suitable window 2 of sufficient size to expose the figures on the marker plate 3, 45 said marker plate being constructed of translucent material such as celluloid, such celluloid plate can be constructed of very thin material and will consequently be more or less flexible and accordingly a back plate 50 4 of heavier translucent material is provided.

5 is a marker plate holding frame of substantially the shape of the front of the casing and adapted to be inserted thereinto

behind the marker plate and the back plate 55 4, said frame having a groove 6 surrounding the central window 7 in such frame. 8 is a rearwardly extending peripheral flange on the frame. 9 is a circular orifice in the upper portion of the frame adapted to register with the corresponding orifice 10 in the upper portion of the front of the casing 1 over which a boss 11 extends provided with the tail lamp bull's eye 12.

13 is the back of the casing provided with 65 a forwardly extending flange 14 adapted to be inserted into the front of the casing and to engage the rearwardly extending flange 8 of the marker holding frame. 15 are bolts extending through the front, frame and 70 back and provided with suitable nuts 16 for securing the respective parts of the casing in position. 17 is a suitably curved reflector provided with the arc-shaped ribs 18 for deflecting the rays of the light from the light 75 19 onto the rear face of the marker plate for illuminating the same.

In assembling the different parts of the device the marker plate 3 is first inserted behind the window 2 in the front of the casing and the backing plate placed behind such marking plate. The frame 5 is then inserted into the casing front behind the backing and the marking plates and such plates are then centered so that they fit into 80 the groove 6 in such frame. The back of the casing 13, to which is secured the reflector 17, is then applied to the front of the casing by inserting the flange 14 into the same. When this is done the forward 85 edge of such flange 14 engages the flange 8 of the frame, thus pressing the same firmly against the backing plate and holding the marking plate and backing plate in the centered position.

90 When the light 19 is turned on it will be seen that the downward rays of the light will be deflected by the reflector 17 onto the rear face of the marker plate, thus illuminating the same. The light 19 will also 100 illuminate the tail lamp bull's eye 12.

95 From the above description it will be apparent that we have devised a combined tail lamp and license marker holder in which the numbers on the marker plate will be 105 visible by day or by night. Further we have devised a holder in which there will be no rattling of the respective parts and in which,

the marker plate can be constructed of very light material and thus can be renewed at a very small cost each year.

What we claim as our invention is:

- 5 1. A combined tail lamp and license marker holder comprising a casing having a window therein, a translucent marker plate inserted into the casing behind said window, a frame inserted into the casing behind said 10 marker plate, said frame having a rearwardly extending peripheral flange, a casing back, having a forwardly extending flange inserted into the casing and adapted to engage the rearwardly extending flange 15 on the frame.
2. A combined tail lamp and license marker holder comprising a casing having a window therein, a translucent marker plate inserted into the casing behind said 20 window, a frame inserted behind said marker plate having a window therein corresponding to the window in the casing and a forward marginal groove in the front thereof around said window to receive the marker 25 plate, said frame having a rearwardly extending peripheral flange, and means for holding the frame in engagement with the marker plate.
3. A combined tail lamp and license 30 marker holder comprising a casing having a window therein, a translucent marker plate inserted into the casing behind said window, a frame inserted behind said marking plate having a window therein corresponding to 35 the window in the casing and a forward marginal groove in the front thereof around said window to receive the marker plate, said frame having a rearwardly extending peripheral flange and a casing back having a 40 forwardly extending flange inserted into the casing and adapted to engage the peripheral flange on the frame.
4. A combined tail lamp and license 45 marker holder comprising a casing having a window therein, a translucent marker plate inserted into the casing behind said window, a frame inserted behind said marker plate having a window therein corresponding to 50 the window in the casing and a forward marginal groove in the front thereof around said window to receive the marking plate, said frame having a rearwardly extending peripheral flange, a casing back having a 55 forwardly extending flange inserted into the casing and adapted to engage the peripheral

flange on the frame and a suitable reflector secured to the forward face of the back.

5. A combined tail lamp and license marker holder comprising a casing having a window in the front thereof, an upper orifice in the front of said casing, an outwardly extending boss surrounding said orifice, a bull's eye in said boss, a translucent marker plate inserted in the casing behind said window, a backing plate of translucent material 60 inserted behind said marker plate, a frame inserted behind said backing plate, said frame having a window corresponding to the window in the front of the casing and having a marginal groove in the front thereof 65 surrounding the window, said marker plate and backing plate inserted into said groove and said frame having a rearwardly extending peripheral flange, an upper orifice in the front of the frame registering with the orifice in the front of the casing, an electric lamp in said casing, a casing back having a forwardly extending flange inserted into the 70 casing and adapted to engage the rearwardly extending flange of the frame and a ribbed 75 reflector secured to the forward face of the casing back.

6. A combined tail lamp and license marker holder comprising a casing having a window in the front thereof, an upper orifice in the front of said casing, an outwardly extending boss surrounding said orifice, a bull's eye in said boss, a translucent marker plate inserted in the casing behind said window, a backing plate of translucent material 80 inserted behind said marker plate, a frame inserted behind said backing plate, said frame having a window corresponding to the window in the front of the casing and having a marginal groove in the front thereof 85 surrounding the window, said marker plate and backing plate inserted into said groove and said frame having a rearwardly extending peripheral flange, an upper orifice in the front of the frame registering with the orifice in the front of the casing, an electric lamp in said casing, a casing back having a forwardly extending flange inserted into the casing and adapted to engage the rearwardly extending flange of the frame 90 and a ribbed reflector secured to the forward face of the casing back and bolts extending through the casing frame and back.

JOSEPH RICHARD PURVIS.
GEORGE HENRY MOSES.
